UNITED STATES PATENT OFFICE

118,110

DESIGN FOR A DRAWER HANDLE OR SIMILAR ARTICLE

Einar W. Dahlgren, Sycamore, Ill.

Application August 29, 1939, Serial No. 86,933

Term of patent 3½ years

To all whom it may concern:

Be it known that I, Einar W. Dahlgren, a citizen of the United States, residing at Sycamore, in the county of De Kalb and State of Illinois, have invented a new, original, and ornamental Design for a Drawer Handle or Similar Article, of which the following is a specification, reference being had to the accompanying drawing, forming part thereof.

In the drawing:

Fig. 1 is a front elevational view of a drawer handle showing my new design.

Fig. 2 is a side elevational view thereof.

Fig. 3 is a top plan view thereof.

The dominant features of the design are shown in full lines.

I claim:

The ornamental design for a drawer handle or similar article, as shown and described.

EINAR W. DAHLGREN.

CERTIFICATE OF CORRECTION.

Design No. 118,110.

December 19, 1939.

EINAR W. DAHLGREN.

It is hereby certified that the above numbered design patent was erroneously issued for a term of three and one-half years, whereas said patent should have been issued for seven years; and that the said Letters Patent should be read with this correction therein that the same may conform to the record of the case in the Patent Office.

Signed and sealed this 13th day of February. A. D. 1940.
